UNITED STATES PATENT OFFICE.

JOHN L. DRAKE, OF TOLEDO, OHIO, ASSIGNOR TO THE LIBBEY-OWENS SHEET GLASS COMPANY, OF TOLEDO, OHIO, A CORPORATION OF OHIO.

SHEET-EDGE BLOCK.

Application filed May 25, 1925. Serial No. 32,555.

The present invention relates to sheet glass apparatus, and has particular reference to means for creating an edge on the sheet being drawn sufficiently strong to prevent narrowing of the sheet.

An important object of the invention is to provide stationary means at both edges of the sheet being drawn from a mass of molten glass, the said means being adapted to form a relatively viscous edge on the sheet to prevent narrowing thereof.

Still another object of the invention is to provide stationary width maintaining means, the said means consisting of substantially a slotted block and having means associated therewith for creating a suction on the edges of the sheet.

A further object of the invention is to provide a sheet glass apparatus including width maintaining means consisting of a slotted block arranged at each edge of the sheet being drawn, the said block being formed preferably from a non-corrosive metal and being formed to permit a circulation of a cooling medium therethrough.

Other objects and advantages of the invention will become apparent during the course of the following description.

In the drawings wherein like numerals are employed to designate like parts throughout the same,

Fig. 1 is a fragmentary view of sheet drawing mechanism showing one of my improved devices in section,

Fig. 2 is a top plan view thereof partly in section for the purposes of illustration,

Fig. 3 is a front view of one of the devices,

Fig. 4 is a top plan, and

Fig. 5 is a similar view showing a portion of the block removed.

In drawing sheet glass in accordance with the Colburn Patent 1,248,809, granted December 4, 1917, a draw-pot 10 containing a mass of molten glass 11 is provided, and a sheet 12 is drawn in the vertical plane a short distance, after which it is deflected over a bending member 13. The glass is then run over a flattening table and through an annealing leir.

In accordance with the Colburn machine a pair of rotatable knurl rolls are provided at both edges and on either side of the sheet to form an edge thereon sufficiently viscous to prevent narrowing of the sheet to an appreciable extent. It is an aim of the present in-

vention to substitute a slotted block for the knurl rolls to obviate the necessity for the driving mechanism and to also cut down the amount of waste that has heretofore been had.

The invention consists of a block designated in its entirety by the numeral 14, and is preferably formed from any of the well-known non-corrosive metals such as monel, nichrome, etc. A slot 15 is provided through which the border portions 16 of the sheet pass. The slot is so shaped that a bead 17 will be formed on the sheet.

A cavity 18 is formed in the block and has communication with the slot 15 by means of the very small passageway 19. A suitable pipe line 20 is connected to the cavity 18 whereby a suction may be created which will function through the passageway 19 and draw the glass within the slot 15 outwardly and away from the center of the sheet. The amount of suction can be controlled to positively hold the sheet edges from contracting while they are within the slotted block but at the same time the suction should not be sufficiently strong to prevent a free passage of the sheet edge through the said block.

To prevent the passageway 19 from becoming filled with glass, the block may be formed in two pieces and the faces between the cavity 18 and slot 15 may be removed a few thousandths of an inch, thus forming the passageway 19 which will be comparatively very small. This will permit the suction to be applied to the edges of the sheet while at the same time the glass will not enter within the said passage.

The block is preferably formed hollow as at 21 to permit a cooling medium 22 to be circulated therethrough. Connections 23 are provided to allow a continuous flow of the cooling medium. The cooling of the edge is preferably localized to the extreme edge or heel of the bead.

The operation of the machine with these width maintaining devices will be slightly different than with the knurled rolls. The edges of the glass sheet being drawn up will be pulled through the slot 15 in the block, and because of the inherent tendencies of molten glass a certain amount of frictional resistance will be had between the moving glass and the sides of the slot. This frictional retardation encourages a lowering of the temperature of the glass which is fur-

ther accelerated by means of the cooling medium 22. The cooling is not so severe that the glass becomes set, but is of such a nature that the glass will be comparatively viscous

5 to the main body of the glass, thus being strong enough to prevent the glass from narrowing at its base. To further assist the blocks in holding the sheet to width a slight suction is applied to the extreme edges, preventing lateral movement of the glass while within the block. A slight contraction may take place after the glass leaves the blocks, but at the same time the edges will be strong enough to prevent a decidedly noticeable contraction.

10 The numeral 24 designates a support for holding the block in operable position with relation to the pot 10. Any form of support may be used whereby various adjustments of the block may be had.

15 It is to be understood that the form of the invention herewith shown and described is to be taken as the preferred embodiment of the same, and that various changes in the 25 shape, size and arrangement of parts may be resorted to without departing from the spirit of the invention or the scope of the subjoined claims.

Claims:

30 1. In sheet glass apparatus including a mass of molten glass, means to draw a sheet therefrom, slotted means arranged at the edges of the sheet being drawn, the edges of the sheet passing through and contacting

35 with said slotted means, means for creating a suction within the slotted means, and means for circulating a cooling medium through said slotted means to prevent narrowing of said sheet.

40 2. In sheet glass apparatus including a mass of molten glass, means for drawing a sheet therefrom, a stationary slotted member arranged above the surface of the glass from which the sheet is drawn, the edges of

the sheet passing through the said slotted 45 member, and means for creating a suction within said member to prevent narrowing of the sheet.

3. In sheet glass apparatus including a mass of molten glass, means for drawing a 50 sheet therefrom, and a block member arranged at each edge of the sheet, each of the block members having a slot therein through which the edges of the sheet pass, and a cavity arranged in proximity to the slot, the 55 cavity having a partial vacuum therein, the slot and cavity being connected whereby the glass in the slot will be urged away from the center of the sheet.

4. In sheet glass apparatus including a 60 mass of molten glass, means for drawing a sheet therefrom, and a slotted block arranged at each edge of the sheet, means for creating a suction on that portion of the glass within the slotted block, and means for 65 lowering the temperature of the block.

5. In sheet glass apparatus including a mass of molten glass, means for drawing a sheet therefrom, a stationary slotted member arranged above the surface of the glass 70 from which the sheet is drawn, the edges of the sheet passing through the said slotted member, means for creating a suction within 75 said slotted member to prevent narrowing of the sheet, and means for circulating a cooling medium through said slotted member.

6. In sheet glass apparatus including a mass of molten glass, means for drawing a sheet therefrom, a slotted block arranged at 80 each edge of the sheet, means for creating a suction on that portion of the glass within the slotted block, and means for circulating a cooling medium through said block.

Signed at Toledo, in the county of Lucas, 85 and State of Ohio, this 22nd day of May, 1925.

JOHN L. DRAKE.
